UNITED STATES PATENT OFFICE

RAYMOND C. PRATT, OF CHICAGO, ILLINOIS

AUTOMOBILE CONDENSER

Application filed March 10, 1930. Serial No. 434,517.

My present invention relates to automobile condensers, and particularly those which are in the nature of attachments for the usual automobile radiator.

5 One object of my present invention is to provide an improved means and method for preventing the loss by evaporation of the cooling medium commonly employed in automobile radiators.

10 Another object of my invention is to provide a means and method of reducing the corrosion in the radiator and to prevent the precipitation of impurities in the radiator.

It has usually been found necessary to add 15 to the supply of cooling medium in automobile radiators from time to time in order to keep the supply therein up to the required level in order to prevent overheating of the motor. Even where the radiator does not leak it is usually necessary at not infrequent 20 intervals to add to the supply of cooling medium in the radiator. This is especially true in the summer time when the cooling medium is usually water and when the operating temperature thereof usually closely approaches the boiling point. It is well known 25 that water contains various chemical salts and other impurities which are left behind when the water is evaporated. Thus the necessary continued addition of water to 30 replenish that evaporated from the radiator has the effect of concentrating these salts and impurities and causes the eventual precipitation of sludge in the radiator with the 35 likelihood of clogging the radiator tubes and the water jacket passages so that the efficiency of the cooling system is greatly reduced.

It is also well known that dissolved oxygen 40 which is usually present in water is one of the factors of corrosion. I propose to reduce corrosion within the radiator and water jacket by reducing the oxygen content of the water in the radiator as by driving off the oxygen by condensing the vapors from the heated liquid without contact with the air.

In the higher altitudes where the boiling point of water or other liquids is consider- 45 ably lower than at sea level, replenishment 50

of the supply in the radiator is necessary even more frequently.

In the winter when the temperature is likely to be below the freezing point of water it is common to employ in automobile radiators a mixture of water and some other liquid whose freezing point is considerably below that of water so that the automobile may be operated during times when the temperature is below 32°. In some localities, alcohol is 55 commonly employed for this purpose, but one disadvantage in the use of alcohol is that its boiling point is considerably lower than that of water so that during the normal operation of automobiles having a mixture of alcohol and water in the radiators thereof there is a continual loss of the alcohol by evaporation, thus leaving behind the water and creating a condition where there is considerable danger that the radiator may be injured by 60 the freezing of the water. 65

The principal objects of my invention, as has been stated are, first, to prevent loss by evaporation of the cooling medium or any volatile ingredients thereof, and, second, to 70 reduce corrosion and prevent the precipitation of sludge in the radiators. In the preferred embodiment of my invention and which will be described later the first result is secured by removing the vapors from the 75 radiator when the liquid therein is heated, cooling and condensing the vapors, and returning the liquid condensate to the radiator. Thus it is that where, prior to my invention, there was a continuous loss of the 80 cooling medium, by my invention all such losses are obviated and there is no longer any necessity for continually having to add water, alcohol or other anti-freeze solution, to 85 the supply of cooling medium in the radiator 90 in order to keep the supply up to the required amount. 95

In the winter time a considerable saving is thus effected by virtue of having to purchase only the required amount of anti-freeze solution at the beginning of the cold season, and in the summer time a real advantage is obtained by use of my invention in that the danger of overheating the motor is considerably reduced. It is well recognized that when 100

for some reason the quantity of cooling medium in the radiator is reduced, as by evaporation, leakage or the like, the heat of the motor will cause this reduced quantity to be heated to a degree higher than would be the case if the radiator was filled to the required level. Thus the liquid remaining in the radiator is evaporated at an increased rate and, prior to my invention, the quantity thereof further reduced which resulted in raising the remaining liquid to an even greater degree of heat, so that in a short time the motor would be overheated with great danger of scoring the cylinder, burning out a bearing, or other ills common to automobile motors.

My invention does away with most of these conditions because all of the vapor arising from the liquid in the radiator is condensed and returned to the radiator so that there is no loss of the liquid, and therefore no occasion under ordinary conditions for the temperature of the cooling medium to further increase.

By the use of my invention one is enabled to safely operate his automobile motor at temperatures sufficiently near the boiling point of water so that an increased economy of fuel is obtained, it being commonly recognized that automobile motors will operate more efficiently at temperatures around the boiling point of water than they will at temperatures below.

The second object is attained by my invention in this manner. The rise in temperature of water when the motor is operated tends to drive off the dissolved oxygen in the water, and since the vapors are returned to the radiator in the form of distilled water it will be seen that my device operates to reduce the oxygen content and hence reduce corrosion of the metal parts in contact with the water. My invention prevents the precipitation of sludge because the vapors are returned to the radiator and it is unnecessary to continually add fresh water and the contained impurities. Thus where prior to my invention the continued additions of water to replace what was evaporated eventually caused a precipitation of sludge due to the concentration of impurities, by the use of my invention such additions are not necessary and the concentration of salts in the water and eventual precipitation of sludge does not take place, excepting the usual decomposition of bicarbonates and precipitation of normal carbonates of the alkaline earths.

Another object of my invention is to provide means to prevent the escape of vapors through the usual overflow pipe, which means is so formed and arranged that under excessive pressure in the radiator the overflow pipe is opened for communication with the atmosphere.

Other objects and advantages of my invention will be apparent to those skilled in the

art to which it appertains after a consideration of the following detailed description of one preferred embodiment of the same which is illustrated in the accompanying drawings, in which:

Figure 1 is an exterior view showing my device mounted on the usual radiator cap; 70

Figure 2 is a vertical cross section showing my device as it would appear when mounted on an automobile radiator; 75

Figure 3 is a horizontal section taken on the line corresponding to the line 3-3 of Figure 2;

Figure 4 is a plan view looking down on my device when the top plate is removed; 80

Figure 5 is a disassembled view showing the different parts of my device;

Figure 6 is an enlarged detailed view showing in vertical cross section the type of biased valve which I employ in connection with the overflow pipe of the radiator; 85

Figure 7 is a vertical sectional view showing one modification of my invention; and

Figure 8 is a plan view, corresponding to Figure 4, looking down on the modification 90 illustrated in Figure 7 and with the top plate removed.

The usual automobile radiator 1 is commonly supplied with a filler opening 2 having an upper threaded end 3 on which is adapted to be secured a radiator cap or closure 4. Some types of radiator closures are not threaded but are secured to the radiator in various ways, but since my invention is not concerned with the particular type of radiator cap, I have shown only the conventional screw threaded cap. The usual overflow pipe for the radiator is indicated by the reference numeral 5.

When my invention is employed the radiator closure 4 is provided with a central opening 7, see Figure 2, which receives the threaded tube 8. The tube 8 extends a short distance below the cap 4 and also extends above the cap 4 a substantial distance and has its upper end 9 threaded to receive an apertured plate 10 thereon. The plate 10 is provided with a down turned peripheral flange 12 for the purpose of receiving the top plate 14 thereon and in leak tight relation therewith. The plates 10 and 14 may be joined together at their edges by soldering, or the like, the plate 14 being also provided with a down turned peripheral flange 15 for this purpose. The flange 15 may be provided with an ornamental bead 16 if desired. The plates 10 and 14 are so formed as to provide therebetween a chamber 20 in communication through the tube 8 with the vapor space of the radiator 1 so that any vapors arising from the liquid in the radiator will pass through the tube 8 and into the chamber 20. 110

A condensing coil of spiral formation is provided for receiving the vapors from the chamber 20, condensing the same, and re- 115

turning the liquid condensate to the radiator. As shown in Figure 4, the plate 10 is provided at one point near the edge thereof with a slit 27 having one edge 28 thereof pressed upwardly and the other edge 29 pressed downwardly so as to provide an opening for the upper end 31 of the coil of tubing 24. The end 31 of the coil 24 is secured to the plate 10 in any desired manner as by soldering, while the other end 32 of the coil 24 is bent to a radial position for the purpose of communicating with the interior of the tube 8.

For this purpose a small fitting 35 having an axial bore and a lateral bore is threaded into the tube 8, as clearly shown in Figure 2. One end of the fitting 35 receives the end 32 of the coil 24, while interiorly of the tube 8 a small pipe 37 is secured in any desired manner within the lateral bore of the fitting 35. Thus a complete circuit is established, the vapor from the radiator being drawn up through the tube 8 into the chamber 20 and the coil 24 where it condenses and forms liquid which then moves downwardly in the coil 24 through the fitting 35 and the small pipe 37 back into the radiator again, the liquid flowing down the coil 24 or the small pipe 37 forming slugs or liquid pistons therein which move downwardly under the action of gravity and thereby serve to draw more vapor up through the tube 8 and into the chamber 20, thus establishing the proper circulation.

In order to prevent escape of vapors through the usual overflow pipe 5, I provide a biased valve 40 which tends to remain closed to prevent the escape of vapors through the overflow pipe 5. The type of biased valve which I preferably employ is one in the form of a tapered rubber plug having downwardly opening lips 41 which will remain closed against upward pressure and will also remain closed against downward pressure up to a certain amount. In the form shown the valve 40 will remain closed against downward pressure, that is, internal pressure in the radiator 1, until the pressure exceeds two or three pounds per square inch. It has been found that under ordinary operating conditions the pressure of the vapors in the radiator 2 rarely exceed two or three pounds per square inch, hence, normally the valve 40 is closed so that all of the vapors passing off the liquid in the radiator will be condensed and returned to the supply in the radiator. The only purpose of the valve 40 is to serve as a means for causing all of the vapors to be condensed while yet allowing the radiator 1 to be vented to the atmosphere in the case of some abnormal condition where more vapor would be formed than could be condensed.

The valve 40 is tapered so that one size of valve may fit two or more sizes of overflow

pipes 5. As shown in Figure 2 the valve 40 is fitted into one of the smaller sizes of pipes for which it is adapted.

Surrounding the coil 24 is a circular casing 50 having a plurality of apertures 51 formed therein for the purpose of allowing atmospheric air to come in contact with the exterior walls of the coil 24 whereby the vapor therein is cooled and condensed. The casing 50 is adapted to be seated within the flange 12 of the upper plate 10 and to be clamped between the plate 10 and a lower plate 55 having a similar flange 56 to receive the casing 50. The plate 55 is provided with a central threaded aperture so that it may be screwed onto the tube 8, as illustrated in Figure 2. The plate 55 may be provided with a pair of holes 57 for the reception of a spanner wrench, whereby the parts may be secured together. The lower end of the tube 8 receives the nut 59 which serves to hold the condenser assembly on a radiator cap or closure 4, and I may also provide a lock nut 60 for the purpose of securing the nut 59 in place.

In forming the casing 50 I contemplate making the same of a single strip of metal, bending the same to circular formation as illustrated in Figure 3 and bringing the ends of the strip in abutting relation, then securing the ends together by means of a plate 63 which may be soldered, welded or otherwise secured to the ends 65 and 66 of the strip forming the casing 50. The tube 24 has abutting contact, as indicated at 64, with the casing 50.

The principal difference between my invention as embodied in the device illustrated in Figure 2 and the modification shown in Figure 7 is that a circular series of relatively short vertical tubes of small diameter are substituted for the coil 24. As shown in Figure 7, an upper chamber is formed by the top plate 70 having a peripheral flange 71 and an upper plate 73 having a similarly formed flange 74. The two plates 70 and 73 are secured together in a manner similar to that described in connection with Figure 2. The upper plate 73 is provided with a central threaded aperture 74' to receive the central tube 76 which is provided with a lower threaded end 77 similar to the tube 8 illustrated in Figure 2. The lower plates 79 and 80 are formed to provide a lower chamber 82 similar to the chamber 83 formed by the plates 70 and 73. These chambers 82 and 83 are in communication with one another through a series of vertical tubes 85 preferably arranged concentric with respect to the central tube 76. These tubes 85 may be threaded into apertures formed in the plate 79 and soldered into apertures formed in the upper plate 73, as shown in Figure 7, or both ends of each of these tubes 85 may be soldered in position if desired.

The plate 80 is provided with an upwardly extending peripheral flange 87 having thread-

ed connection with flange 88 formed on the plate 79, and at its lower and central portion the plate 80 has secured thereto, as by soldering, a nut member 90.

As made clear in Figure 7, the lower plate 80 has an aperture 91 of larger diameter than the tube 76 for the purpose of allowing communication between the chamber 82 and a series of vertical apertures 93 extending around the tube 76 and opening into an annular groove 95 formed in the nut member 90. A series of apertures 97 are formed in the tube 76 in a position to be opposite the annular groove 95 when the parts are in assembled relation. A nut 98 threaded on the tube 76 serves to secure the condenser in position on the radiator cap or closure 4, and a lock nut 99 may be provided to maintain the nut 98 tight. A gasket 100 may be interposed between the nut member 90 and the top of the radiator cap.

A casing 102 similar to the casing 50 of Figure 1 is mounted between the plates 73 and 79 and held in place therein by the flanges 74 and 88. The casing 102 is provided with a series or plurality of openings 103 therein for the same purpose as the openings 51 in the casing 50.

The operation of the modified form of my invention illustrated in Figure 7 is substantially the same as the operation of the form illustrated in Figure 2. The vapor is cooled and condensed in tubes 85, which are subjected to contact with the atmospheric air through the openings 103, and the liquid condensate runs out of the tubes 85 drawing more vapor up through the tube 76 and into the chamber 83, then through the chamber 82 and the openings 93 into the groove 95 from whence it flows back into the radiator through the openings 97.

If the rate of condensation is not such that liquid slugs are formed in the tubes 85, then the liquid condensate runs down the inside of the tubes 85 into the chamber 82 and collects in a pool in or above the annular groove 95 from which it escapes through openings 97 back into the radiator, and in so escaping serves to draw more vapor up through the central tube 76, thus establishing the proper circulation.

The biased valve 40 is employed with both of the modifications illustrated in Figures 2 and 7, respectively.

While I have described, in connection with the accompanying drawings, the specific forms in which I prefer to embody my invention, it is to be understood that the invention is not to be limited to the specific means which I have herein shown and described, and that, in fact, widely different means may be employed in the practice in the broader aspects of my invention.

What I claim, therefore, and desire to secure by Letters Patent is:

1. A condenser for radiators comprising means leading into the vapor space of the radiator and adapted to convey vapor therefrom, and means including relatively small tubing in communication with the top of said first named means and leading back into communication with the radiator, said last named means also including a conduit means in communication with the tubing and passing through said first named means. 70 75

2. A condenser for radiators comprising means leading into the vapor space of the radiator and adapted to convey vapor therefrom, and means including relatively small tubing in communication with the top of said first named means and leading back into communication with the radiator, said last named means also including means forming a chamber at the lower end of said tubing and a conduit in communication with said chamber and passing through said first named means. 80 85

3. A condenser for automobile radiators comprising, in combination, a tube communicating at one end with the vapor space of said radiator, a pair of plates formed to provide a chamber therebetween, one of said plates having threaded connection with said tube, said tube and chamber being adapted to receive vapor from the heated liquid in the radiator, a coil of relatively small tubing in communication with the chamber and adapted to receive vapor therefrom, said coil arranged to be cooled by the atmosphere so as to thereby condense the vapor therein and leading downwardly so that the liquid condensate flows out under the action of gravity, a second tube within said first named tube and having a fitting extended therethrough for connection to said coil, and means to secure the condenser to the radiator. 90 95 100

4. A condenser for automobile radiators comprising, in combination, a tube communicating at one end with the vapor space of said radiator, a pair of plates formed to provide a chamber therebetween, one of said plates having threaded connection with said tube, said tube and chamber being adapted to receive vapor from the heated liquid in the radiator, a coil of relatively small tubing in communication with the chamber and adapted to receive vapor therefrom, said coil arranged to be cooled by the atmosphere so as to thereby condense the vapor therein and leading downwardly so that the liquid condensate flows out under the action of gravity, a second tube within said first named tube and having a fitting extended therethrough for connection to said coil, a perforated casing surrounding the coil, a plate threaded on said first tube and adapted to hold the casing in place, and means to clamp a radiator cap to the last named plate. 110 115 120 125

5. In a device of the class described, the 130

combination with a radiator having a radiator closure and an overflow pipe, of a condenser comprising means leading into the radiator through an opening in said closure and adapted to convey vapor therefrom, a chamber at the top thereof, and means including relatively small tubing leading from the chamber and terminating above said closure in said conveying means, and tube means enclosed by said conveying means and leading back into the radiator, and a yielding, valve associated with said overflow pipe to establish a predetermined maximum pressure within said radiator, said valve opening outwardly to vent the radiator to the atmosphere when said predetermined pressure is exceeded.

6. A condenser for radiators comprising a conduit leading into the radiator and adapted to convey vapor therefrom, said conduit being enlarged at its upper end to provide a closed chamber and the enlarged portion of the conduit having a slot therein with one edge of the slot struck inwardly and the other struck outwardly, and a conduit passing through the slot and lying in the channel so formed, leading back into the radiator for condensing the vapor and conducting the condensate back into the radiator.

7. A condenser for radiators comprising a conduit leading into the radiator and adapted to convey vapor therefrom, said conduit being enlarged at its upper end to provide a closed chamber, a coil of relatively small tubing terminating in said chamber, the enlarged portion of the conduit having means struck therefrom for securing the end of said tubing terminating in said chamber, and means for connecting the other end of said tubing with said conduit for leading the condensed vapor back into the radiator.

In witness whereof, I hereunto subscribe my name this 7th day of March, 1930.

RAYMOND C. PRATT.
